UNITED STATES PATENT OFFICE

JOSEPH SACHS, OF WEST HARTFORD, CONNECTICUT

ELECTRIC-METER SERVICE APPLIANCE

Original application filed February 8, 1927, Serial No. 165,645. Divided and this application filed January 18, 1931. Serial No. 247,730.

This invention relates particularly to fused switch appliances of the type disclosed in my patent for electric circuit controlling appliances, No. 1,754,445 issued April 15, 1930, this 5 patent having been based upon application Serial No. 165,645 filed February 8, 1927, of which this present application is a division.

The object of the present invention is to provide in combination with a fused switch 10 appliance of the type referred to suitable meter testing facilities which are conveniently located and which are supported and connected in a novel and advantageous manner.

In the accompanying drawings I have 15 shown one embodiment of the invention but it will be understood that the drawings are intended for illustrative purposes only and are not to be construed as defining or limiting the scope of the invention, the claims forming 20 a part of this specification being relied upon for that purpose.

Of the drawings:

Fig. 1 is a front view of an appliance embodying the invention the front cover being 25 broken away to show interior parts.

Fig. 2 is a bottom view of the fused switch appliance, this view also showing the enclosing cabinet in section.

Fig. 3 is a fragmentary side view of the 30 parts shown in Fig. 1, certain portions of the enclosing cabinet being shown in section.

Fig. 4 is a fragmentary front view similar 35 to Fig. 1 but showing the fuse base and one of the blocks carrying the testing elements removed in order that other parts may be more clearly shown.

Fig. 5 is a fragmentary vertical sectional view taken along the line 5—5 of Fig. 1.

Fig. 6 is a fragmentary vertical sectional 40 view taken along the line 6—6 of Fig. 4.

Fig. 7 is a fragmentary vertical sectional view similar to Fig. 5 but showing an alternate embodiment of the invention.

In the embodiment of the invention shown 45 in the drawings, there are two pairs of fuse contacts and two separate switching devices, but it will be understood that the invention is not necessarily limited to any particular number of fuses and switches. The fuse and 50 switch contacts and also the meter testing fa-

cilities are shown symmetrically disposed with respect to the vertical central plane of the appliance, and for the sake of convenience and simplicity of description, I will describe in detail only those parts on one side of the 55 said plane, it being understood that the parts on the other side are, or may be, the same in construction except for reversal of positions.

Fuse receiving contacts 1 and 2 are provided on the front face of an insulating base 3. Means are provided for supporting the base 3 in fixed spaced relationship to a rear support. When there is an enclosing cabinet this support may be the rear wall of the cabinet. The fuse contacts as shown are adapted 60 for receiving a cartridge enclosed fuse such as F, but it will be understood that the invention is not limited for use with fuses of this particular type.

In addition to the main rear support, I 65 prefer to also provide an independent insulating supporting device which is ordinarily secured to the main rear support but which is nevertheless separate therefrom. This supporting device is shown at 4, 4 in the drawings and may comprise two separated bars 70 of insulating material. When such a separate supporting device is provided, the fuse contacts and the base are also normally held 75 in fixed spaced relationship therewith.

Preferably, a plurality of supporting elements 80 are provided which are connected at their forward portions with the base and at their rear portions with the main rear support, preferably indirectly by means of the 85 separate supporting device 4, 4. The supporting elements are preferably formed of metal and they serve to support the fuse contacts and the base in the described relationship with the said rear support. As shown, 90 there are at least two such supporting elements for each pair of fuse contacts, these being represented at 5 and 6 respectively. The supporting elements 5 and 6 are shown as being Z-shaped, but as to this there may be 95 variation. The supporting elements have their rear portions connected with the supporting device 4, 4 by means of screws 7, 7. Suitable means such as screws 8, 8 are provided for mechanically connecting the for- 100

ward portions of the supporting elements with the fuse base 3, the screws extending through holes 9, 9 in the said base. These screws 8, 8 preferably also serve to electrically connect the fuse contacts with the respective supporting elements, but I do not necessarily limit myself to the use of the same screws or other holding means for providing both mechanical and an electrical connection.

- 10 Located at least in part in the space behind a vertical plane extending through the rear parts of the base 3 is a switching device, which comprises at least one and preferably two stationary switch contacts such as 10 and 11. 15 As concerns some of the broader phases of the invention, the construction and mounting of the stationary switch contacts of the switching device can be varied, but, preferably and in accordance with other phases of the invention, at least one and preferably two of the said switch contacts 10 and 11 are mounted directly upon and electrically connected with corresponding supporting elements 5 and 6. One or both of the supporting elements 5 and 6 are electrically connected with 25 one or both of the fuse contacts 1 and 2.

Preferably each of the said switch contacts 10 and 11 is one of a pair. The other contacts of the pairs are shown at 12 and 13 respectively and they are similar respectively to the contacts 10 and 11 but oppositely positioned. Two pairs of stationary switch contacts are shown but the invention is not so limited. Contact supporting elements 14 and 15 are 30 provided for the contacts 12 and 13, these preferably being similar to the main supporting elements 5 and 6 and being similarly secured to the supporting device 4, 4 as by screws 7', 7'. Connected with each supporting element 14 is a wire connecting terminal 16. I have shown a terminal of the solder lug type, but I do not so limit myself.

For establishing or breaking electrical connection between the switch contacts of the said pairs 10, 12 and 11, 13, I preferably provide for each pair a switching element which is rectilinearly movable substantially parallel with the front face of the supporting device and with the rear face of the fuse base. When there are two pairs of stationary switch contacts there are two conducting switching elements 17 and 18 insulated from each other and adapted respectively to engage and disengage the said stationary switch contacts. The two conducting switching elements 17 and 18 are preferably carried by an insulating element 19, which with the said conducting elements constitutes a rectilinearly movable switching member. The insulating element 19 is preferably in the form of a flat plate, the said conducting elements 17 and 18 extending through it and projecting somewhat beyond the opposed surfaces thereof as shown. The details of the switching member may be as shown in my patent for

electric circuit controlling appliance, No. 1,754,444 issued April 15, 1930. When the stationary switch contacts are located as shown, the said flat insulating element 19 is arranged perpendicularly to the supporting device and to the fuse base. The said element may extend into a groove 20 formed in the base 3.

From the foregoing description, it will be apparent that when the switching member is 75 in the "on" position as shown, a circuit will be established from the wire connecting terminal 16 through the contact supporting element 14 and the switch contacts 12, 17, and 10, to the supporting element 5 and thence 80 to the fuse contact 1. Similarly a connection is established from the fuse contact 2 through the supporting element 6 and the switch contacts 11, 18 and 13 to the contact supporting element 15. When the switching member is moved upward from the position shown, the elements 17 and 18 will be disengaged from the stationary switch contacts and circuit will be broken at two points at each side of the fuse, thus making a total 90 of four breaks. Although the switching member is guided between the base 3 and the supporting device 4, 4 and is held by these parts against forward or backward movement, it is entirely free to adjust itself laterally to conform to the positions of the several 95 stationary switch contacts.

When there are two switching devices as shown and described, there may be provided an insulating baffle plate 21 located between 100 them. This is shown as being held in a slot in the fuse base 3.

I have shown an enclosing cabinet 22 of sheet metal having a rear wall 23, side walls 24, 24 and end walls 25 and 26. The upper end wall 25 preferably has an opening therein which adapts the cabinet for direct protective relationship with an electric meter such as M. As shown the terminal chamber portion projects through the said opening in the end wall 25. The cabinet has an openable front cover 27, which is shown as being hinged at 27' to the bottom end wall 26. Suitable means such as a spring latch 28 is provided for holding the cover in closed position and a seal 29 may be provided for preventing the opening of the cover except by breaking the seal. The fused switch unit as a whole is secured to the rear wall 23 of the cabinet by means of screws 30, 30 engaging 115 the supporting device 4, 4. If preferred a sheet of insulating material may be interposed between the device 4, 4 and the cabinet wall 23.

For operating the switch members there is 120 provided a spindle 31 including two pivot sections 32 and 33 extending through bearing openings in the side walls 24, 24 of the cabinet. The said spindle is bent to form 125 a manually operable handle 34 outside of the 130

5 cabinet and also to form a crank section 35 inside of the cabinet and between the pivot sections. In each insulating element 19 there is a slot 37 adapted to receive the crank section 35. The slot 37 is preferably open at one end, that is, at the back end, so as to facilitate assembly or disassembly of the fused switch unit to or from the cabinet. The slot 37 is shown as being near the middle of the insulating element, this location being ordinarily preferable, but it will be understood that I do not limit myself to this location. The 10 baffle plate 21 is provided with an opening to provide clearance for the crank section 35 of the operating spindle. Preferably, the cabinet is provided with a handle stop member 38. By moving the handle 34 each of the switch members can be moved longitudinally upward or downward, as desired. With the 15 handle 34 in its uppermost position A as shown in Fig. 3, the switching members will be held in their lowermost positions thus completing the circuit through the switch and fuse contacts as described. When the handle 20 34 is moved to its lowermost position B as shown in Fig. 3, the switching members will be moved to their uppermost positions, thus separating the movable contacts 17 and 18 from the stationary contacts 10, 12 and 11, 25 13 respectively and thus breaking each leg of the circuit at four points as already fully described.

30 The cabinet cover 27 is provided with an opening 39 through which the said fuses and contacts are accessible. The relationship between the cover and fuse base 3 is such that an extension 41 on the base serves to entirely close the opening 39 when the cover is in closed position. I preferably provide an auxiliary fuse cover for the opening 39 and I further preferably so construct the parts that the fuse cover cannot be opened when the switch handle 34 is in the position corresponding to the closed position of the switch and so that the handle 34 cannot be moved to the position corresponding to the closed position of the switch when the cover is open. I have shown a sidewise opening flat cover 42 for the fuses, this cover preferably directly engaging the main cover 27 for sliding movement thereon. Rigidly secured to the main cover 27 is a sheet metal guide 43 having an opening 44 thereon which registers with the opening 39 in the main cover. The guide 43 is spaced from the main cover so that the fuse cover 43 is slidably mounted between the said parts. The said fuse cover 42 is provided with a knob 45 which serves as a means for moving the fuse cover and which also serves as a stop for limiting the movement of the said cover in either direction. Fig. 2 shows the cover 42 in its left hand closed position. It will be observed that when the fuse cover is in closed position and the handle 34 in the switch closing position, the said handle di-

rectly obstructs the cover and prevents the opening movement thereof. When the fuse cover is in its open position having been moved to the right from the position shown in Fig. 2, the said cover directly obstructs the handle 34 and prevents its movement to switch closing position.

5 In addition to the parts already described, I have provided elements for facilitating the testing of the meter. The details of the testing facilities may be varied according to the conditions of use. For three wire service I preferably provide testing facilities for each of two legs of the circuit, the said testing facilities for each leg comprising at least one movable test link adapted to be included in the circuit between the meter and the load wires and adapted to be so moved as to disconnect the meter from the load wires while testing is being carried on.

10 The testing facilities or elements for the respective legs are preferably located at the sides of the base 3 and are supported by means of supporting elements, such as those which support the base. The said supporting elements serve to support the testing elements in fixed spaced relationship with the rear insulating supporting device. The manner of support for the said testing elements may be varied as to details, but by way of illustration I have shown them as supported otherwise than directly on the base 3. Two 15 separate insulating members or blocks 46, 46 are provided for carrying the testing elements for the two circuit legs.

20 The supporting elements for each of the members 46 may include the corresponding supporting element 15 which carries the corresponding switch contact 13. The said supporting element 15 is preferably provided with an off-set downward extension 47 with which the said insulating element directly engages. Preferably in addition to the supporting element 15 there is provided another supporting means which may be a supporting element 48 connected to the supporting device 4, 4 by suitable means such as screws 49, 49. The insulating element 46 is connected to the supporting element 48 by means of a screw 50.

25 Ordinarily and preferably, the incoming circuit wires S, S are connected with the terminals 16, 16, and as shown a neutral wire S' is also provided. The circuit extends from the terminals 16, 16, through the switch and fuse parts in the manner already described to terminals 51, 51 on the respective blocks 46, 46, preferably near the tops thereof, these latter terminals being connected with the supporting elements 15, 15 in a manner to be described in detail. The said terminals 51, 51 are indirectly connected with the outgoing or load circuit wires through the meter M, connections C¹ and C² extending from the said terminals 51, 51 to the meter. Other me-

ter connections C³ and C⁴ extend from the meter M to wire connecting terminals 52, 52 mounted on the blocks 46, 46 adjacent the terminals 51, 51. The outgoing circuit wires L, L are connected directly with terminals 53, 53 which terminals are connected respectively with the terminals 52, 52 by means of movable testing links 54, 54. As illustrated the links 54, 54 are entirely removable, but this is not essential. The testing links 54, 54 as shown are of a well known construction, each link being slotted near its ends and thus adapted to receive studs 55 and 56 connected respectively with the corresponding terminals 52 and 53. Each link has an insulating handle 54'. It will be seen that by removing the links 54, 54 the circuit may be broken between the said terminals 52, 52 and 53, 53.

Preferably, in addition to the testing links 54, 54 I provide other similar links 57, 57 interposed between the terminals 51, 51 and the corresponding switch contact supporting elements 15, 15. As already stated each element 15 is provided with an extension 47. At the front of each block is a short conductor 58 connected with the corresponding extension 47 by means of studs 59 and 60. The corresponding testing link 57 is connected with the stud 60 and with a similar stud 61 connected with the terminal 51.

In addition to the removable links 54, 54 and 57, 57 I also provide contacts adapted for the attachment of by-passing connections from the switch contact supporting element 15, 15 to the terminal 53, 53. For this purpose, I utilize at each side the before-mentioned stud 59 and a similar stud 62 connected with the said terminal 53. Links 63, 63 may be provided as shown in dot-and-dash lines in Figs. 1 to 3 for connecting the said studs 59, 59 and 62, 62. It will be seen that when the links 63, 63 are in place, the circuit will extend directly through the switch and fuse to the load terminals 53, 53. It is then possible to either partly or entirely disconnect the meter and electrically free the terminals thereof by removing some or all of the links 54, 54 and 57, 57.

The general arrangement of switch and fuse parts with the testing elements at the sides of the fuses is not herein broadly claimed being set forth in my copending application for electric meter service appliance, Serial No. 715,320, filed May 23rd, 1924. The specific meter testing devices herein shown and described do not of themselves constitute a part of the present invention, being set forth and claimed in my copending application for electric meter service appliance, Serial No. 170,784 filed February 25, 1927.

From the foregoing description it will be apparent that, in the illustrated embodiment of the invention the fuse base and the blocks for the testing elements are supported independently of each other, although the inven-

tion is not so limited. As shown the said base and blocks are independently supported by means of separate supporting elements extending forward from the rear supporting device 4, 4. Preferably the same supporting elements, or some of them, serve to support the stationary contacts of the switch device. As shown the two supporting elements for the stationary switch contacts of one pair serve respectively to partly support the base and the block for the corresponding testing elements. Access may be had to the fuses through the cover opening as already described without in any way exposing or providing access to the testing means.

The supporting elements 5, 5 and 6, 6 have been described as connected with the fuse base 3. The base may be rigidly and permanently connected with these elements if so desired, but I prefer to detachably connect it or at least movably connect it, so that it can be moved or removed from the normal position in order to permit free access to the switching device. The fuse base is shown as being so mounted that it can be completely detached from the supporting elements by merely unscrewing the screws 8, 8. Preferably in order that the contacts 1 and 2 may be retained upon the fuse base when the base is detached, each of the screws 8 carries a washer 64 located in a recess 65 in the base. It will be obvious that as the screw 8 is withdrawn from the supporting element the washer 64 will move forward in the recess 65, but that the washer will engage the front surface of the recess to prevent complete withdrawal of the screw, thus holding the fuse contact in place on the base.

The movable member of the switching device is adapted to be freely removed from the stationary switch contacts in the forward direction. When the member is removed, the stationary switch contacts may be more easily inspected or cleaned and the conducting contacts 17 and 18 may be more readily inspected or cleaned. The fuse base when in place as described normally engages the forward edge of the switching member to hold it and guide it for rectilinear movement; but when the fuse block is removed, the rectilinearly movable switching member is entirely exposed and is entirely free to be removed in a forward direction. In this connection it will be observed that the slot 37 is open toward the rear, thus permitting the aforesaid forward removal of the switching member.

In Fig. 7 I have shown a construction similar to that shown in Figs. 1 to 6 but differing in that the fuse block is mounted that it may be readily removed by direct manual action and without the use of tools. Instead of providing means such as the screws 8, 8 for providing both an electrical connection and a positive mechanical connection with

the supporting elements, I have provided frictionally acting resilient devices of which one is shown at 8^a. The element 8^a is in the form of a screw which serves to hold the corresponding fuse clip 1 in position, this screw engaging and being held by a nut 66 located in a recess 67. The rear end of the screw 8^a is split as shown at 68 and it normally enters and engages the sides of an unthreaded hole formed in the corresponding supporting element 5^a. Thus the element 8^a serves to establish an electrical connection between the fuse contact and the corresponding supporting element carrying the corresponding stationary switch contact, but no positive mechanical connection is provided, the fuse block being free to be manually removed in a forward direction.

I may provide interchangeable fuse blocks so that any one of several fuse blocks adapted for holding fuses of different electrical characteristics, may be connected with the other parts of the appliance without any extensive changes in the said parts. In Fig. 7 I have shown a longer fuse base 3^a, this base carrying fuse contacts, such as 1^a, constructed and spaced for receiving a fuse F^a longer than the fuse F and having different electrical characteristics. Each of the fuse contacts is held in place on the base by means of a screw 69 and each of them is provided with an extension 70 having a hole therein through which extends the corresponding connecting screw, such as at 8^a. The fuse base 3^a is considerably longer than the fuse base 3 and accordingly a corresponding cabinet cover (not shown) is provided having an opening therein corresponding in length to the length of the fuse base 3^a.

It will be observed that the separate mounting of the fuse base and of the supporting block for the meter testing elements makes it possible for the base to be removed or interchanged as described without in any way interfering with or affecting the said testing elements or the wiring connections. The positions of the testing elements are such that they do not in any way interfere with the inspection or adjustment of the switch parts upon removal of the base.

What I claim is:

1. In an electric meter service appliance, the combination of rear insulating supporting device, a plurality of supporting elements 55 structurally separate from the supporting device and projecting forward therefrom, a switch device located at the front of the supporting device and comprising a pair of stationary switch contacts and a switching element movable to make and break electrical connection between the said contacts, an insulating base supported at least in part upon some of the said supporting elements in normally fixed spaced relationship with the rear insulating supporting device and in front of

the switch device, a pair of fuse receiving contacts on the base, and meter testing facilities also supported at least in part upon some of the said separate supporting elements in fixed spaced relationship with the rear insulating supporting device. 70

2. In an electric meter service appliance, the combination of a rear support, a plurality of supporting elements structurally separate from the support and projecting forward 75 therefrom, a switch device located at the front of the support and comprising a pair of stationary switch contacts and a switching element movable to make and break electrical connection between the said contacts, an insulating base supported at least in part upon some of the said supporting elements in normally fixed spaced relationship with the rear support and in front of the switch device, a pair of fuse contacts on the base, an insulating member separate from the base in fixed spaced relationship with the rear support and supported at least in part on supporting elements other than those upon which the base 80 is supported, and meter testing elements carried by the said separate insulating member. 85

3. In an electric meter service appliance, the combination of rear insulating supporting device, a plurality of supporting elements structurally separate from the supporting device and projecting forward therefrom, a switch device located at the front of the supporting device and comprising a pair of stationary switch contacts and a switching element movable to make and break electrical connection between the said contacts, an insulating base supported at least in part upon some of the said supporting elements in normally fixed spaced relationship with the rear insulating supporting device and in front of 90 the switch device, a pair of fuse contacts on the base, an insulating member separate from the base in fixed spaced relationship with the rear insulating supporting device and supported at least in part on supporting elements 95 other than those upon which the base is supported, and meter testing elements carried by the said separate insulating member. 100

4. In an electric meter service appliance, the combination of a rear support, a plurality of supporting elements structurally separate from the support and projecting forward therefrom, a switch device located at the front of the support and comprising a pair of stationary switch contacts carried respectively by two of the said supporting elements and also comprising a switching element movable between the said contacts to make and break electrical connection between them, an insulating base supported in part 115 upon the said supporting elements in normally fixed spaced relationship with the rear support and in front of the switch device, a pair of fuse receiving contacts on the base, and meter testing facilities also supported in 120 125 front of the switch device. 130

part upon the said supporting elements in fixed spaced relationship with the rear support.

5. In an electric meter service appliance, the combination of a rear support, a pair of supporting elements structurally separate from the support and projecting forward therefrom, a pair of opposed stationary switch contacts carried respectively by the said supporting elements, a switching element movable between the said contacts to make and break electrical connection between them, an insulating base supported in part on one of the said supporting elements, in normally fixed spaced relationship with the said support, a pair of fuse receiving contacts on the base, an insulating member separate from the base and supported independently thereof in part on the other supporting element in fixed spaced relationship with the rear support, and meter testing elements carried by the said separate insulating member.

6. In an electric meter service appliance, the combination of a rear support, a pair of metallic supporting elements projecting forward from the support, a pair of opposed stationary switch contacts mounted upon and electrically connected with the respective supporting elements, a switching element movable between the said contacts to make and break electrical connection between them, an insulating base supported in part on one of the said supporting elements, in normally fixed spaced relationship with the rear support, a pair of fuse receiving contacts on the base, a conducting element extending through the base and electrically connecting the last said supporting element with one fuse contact, an insulating member separate from the base and supported independently thereof in part on the other supporting element in normally fixed spaced relationship with the rear support, meter testing elements carried by the separate said insulating member, and a conducting element extending through the insulating member and electrically connecting the other supporting element with one of the testing elements.

7. In an electric meter service appliance, the combination of a rear support, two pairs of metallic supporting elements projecting forward from the support, an insulating base supported in part on one supporting element of each of the said pairs, in normally fixed spaced relationship with the rear support, a pair of fuse receiving contacts on the base at the front thereof, and electrically connected respectively with one supporting element of each of the said pairs, two pairs of opposed stationary switch contacts mounted on and electrically connected with the respective supporting elements, a rectilinearly movable switching member engaging at its front edge with the said base to be guided in part thereby and comprising two spaced conduct-

ing elements movable respectively between the contacts of the said pairs to make and break electrical connection between them, an insulating member separate from the base and supported independently thereof in part on the other supporting element of one of the said pairs, in fixed spaced relationship with the rear support and meter testing elements carried by the said insulating member with one of the said testing elements electrically connected with the last said supporting element.

8. In an electric meter service appliance, the combination of a rear insulating supporting device, two pairs of supporting elements structurally separate from the supporting device and projecting forward therefrom, an insulating base supported in part on one supporting element of each of the said pairs, a pair of fuse receiving contacts on the base at the front thereof, two pairs of opposed stationary switch contacts mounted respectively on the said supporting elements, a rectilinearly movable switching member engaging at its front edge with the said base to be guided in part thereby and engaging at its rear edge with the supporting device to be guided in part thereby, the said switching member comprising two spaced conducting elements movable respectively between the contacts of the said pairs to make and break electrical connection between them, an insulating member separate from the base and supported independently thereof in part on the other supporting element of one of the said pairs, in fixed spaced relationship with the said supporting device, and meter testing elements carried by the said separate insulating member.

9. In an electric meter service appliance, the combination of a rear support, two pairs of supporting elements structurally separate from the support, and projecting forward therefrom, an insulating base supported in part on one supporting element of each of the said pairs in normally fixed spaced relationship with the rear support, a pair of fuse receiving contacts on the base at the front thereof, two pairs of opposed stationary switch contacts mounted respectively on the said supporting elements, a rectilinearly movable switching member engaging at its front edge with the said base to be guided in part thereby and comprising two spaced conducting elements movable respectively between the contacts of the said pairs to make and break electrical connection between them, an insulating member separate from the base and supported independently thereof in part on the other supporting element of one of the said pairs in fixed spaced relationship with the rear support, meter testing elements carried by the said separate insulating member, and an additional supporting element for the said separate insulating mem-

ber structurally separate from the rear support and projecting forward therefrom.

10. In an electric meter service appliance, the combination of a rear support, a switch device located at the front of the support and comprising two stationary contacts and a contact element movable to make and break electrical connection between them, an insulating base, a pair of fuse receiving contacts on the base, means for detachably and removably supporting the base upon the said support in normally fixed spaced relationship therewith and in front of at least a portion of the switch device, meter testing facilities 15 and means carried by the support independently of the said base for supporting the said meter testing facilities in fixed spaced relationship with the support and for holding it against removal with the base.

20. 11. In an electric meter service appliance, the combination of a rear support, a switch device located at the front of the support and comprising two stationary contacts and a contact element movable to make and break electrical connection between them, an insulating base, a pair of fuse receiving contacts on the base, means for detachably and removably supporting the base upon the said support in normally fixed spaced relationship therewith and in front of at least a portion of the switch device, the said supporting means permitting free access to the switch device from the front when the fuse base and the contacts carried thereby are removed, meter testing facilities, and means carried by the support independently of the said base for supporting the said meter testing facilities at one side of the base and in spaced relationship with the said support and 40 for holding it against removal with the base.

45. 12. In an electric meter service appliance, the combination of a rear support, a switch device located at the front of the support and comprising two stationary contacts and a contact element movable to make and break electrical connection between them, a plurality of interchangeable insulating bases a plurality of pairs of fuse receiving contacts on the respective bases, adapted for receiving fuses having different electrical characteristics, means for detachably and removably supporting any one of the bases upon the said support in normally fixed spaced relationship therewith and in front of at 55 least a portion of the switch device, the said supporting means permitting one base and the fuse contacts carried thereby to be removed and another put in place, meter testing facilities, and means carried by the support independently of any of the said bases for supporting the said meter testing facilities in fixed spaced relationship with the support and for holding it against removal with 65 the bases.

13. In an electric meter service appliance, the combination of a rear support, two pairs of opposed stationary switch contacts located at the front of the support, a movable switching member comprising two conducting elements respectively movable between the said contacts of the corresponding pairs to make and break electrical connection between them, an insulating base, a pair of fuse receiving contacts on the base, means for detachably and removably supporting the base upon the said support in normally fixed spaced relationship therewith and in front of at least a portion of the switching member, the said supporting means permitting free 80 access to the switch contacts and the switching member from the front when the fuse base and the contacts carried thereby are removed, meter testing facilities, and means carried by the support independently of the 85 said base for supporting the meter testing facilities in fixed spaced relationship with the support and for holding it against removal with the base.

14. In an electric meter service appliance, 90 the combination of a rear support, two pairs of metallic supporting elements projecting forward from the support, an insulating base, means for detachably and removably supporting the base upon one supporting element of each of the said pairs, in normally fixed spaced relationship with the rear support, a pair of fuse receiving contacts on the base at the front thereof, and electrically connected respectively with the last said supporting elements, two pairs of opposed stationary switch contacts mounted on and electrically connected with the respective supporting elements, a rectilinearly movable switching member engaging at its front edge 100 with the said base so as to be guided thereby 105 and so as to be removable in the forward direction when the base is removed, the said switching member comprising two spaced conducting elements movable respectively 110 between the contacts of the said pairs to make and break electrical connection between them, an insulating member separate from the base and supported independently thereof in part on the other supporting element of one of the said pairs, in fixed spaced relationship 115 with the rear support, and meter testing elements carried by the said separate insulating member with one of the testing elements electrically connected with the last said supporting element.

15. In an electric meter service appliance, the combination of a rear insulating supporting device comprising two separated parallel bars, supporting elements structurally separate from the respective bars, and projecting forward therefrom, an insulating base supported on supporting elements projecting from both bars, and thereby held in normally fixed spaced relationship with the said 130

bars, a pair of fuse receiving contacts on the base at the front thereof, a switch device located at least in part behind the base and comprising two stationary switch contacts carried by the supporting device and an element movable to make and break electrical connection between the said contacts, an insulating member separate from the base and supported independently thereof on supporting elements projecting from both bars, and thereby held in fixed spaced relationship with the bars, and meter testing elements carried by the said separate insulating member.

15 16. In an electric meter service appliance, the combination of a rear insulating supporting device comprising two separated parallel bars, supporting elements structurally separate from the respective bars and projecting forward therefrom, an insulating base supported in part on one supporting element of each of the said pairs, and thereby held in normally fixed spaced relationship with the said bars, a pair of fuse receiving contacts on the base at the front thereof, two pairs of opposed stationary switch contacts mounted respectively on the said supporting elements, a rectilinearly movable switching member engaging at its front edge with the said base to be guided in part thereby and engaging at its near edge with the bars of the supporting device to be guided in part thereby, the said switching member comprising two spaced conducting elements movable respectively between the contacts of the said pairs to make and break electrical connection between them, an insulating member separate from the base and supported independently thereof in part on the other supporting element of one of the said pairs, and thereby held in fixed spaced relationship with the said bars, meter testing elements carried by the said separate insulating member, and an operating device for the switching member located in part in the space behind the base and the insulating member and between the supporting elements projecting forward from the respective bars of the supporting device.

20 25 30 35 40 45 50 55 60 65 17. In an electric meter service appliance, the combination of a rear insulating supporting device comprising two separated parallel bars, two pairs of metallic supporting elements projecting forward from the respective bars, an insulating base supported in part on one supporting element of each of the said pairs, and thereby held in normally fixed spaced relationship with the said bars, a pair of fuse receiving contacts on the base at the front thereof, and electrically connected respectively with the last said supporting elements, two pairs of opposed stationary switch contacts mounted on and electrically connected with the respective supporting elements, a rectilinearly movable switching member engaging at its front edge with the said base to be guided in part thereby and engaging at its rear edge with the bars of the supporting device to be guided in part thereby, the said switching member comprising two spaced conducting elements movable respectively between the contacts of the said pairs to make and break electrical connection between them, an insulating member separate from the base and supported independently thereof in part on the other

supporting element of one of the said pairs, and thereby held in fixed spaced relationship with the said bars, and meter testing elements carried by the said separate insulating member with one of the testing elements electrically connected with the last said supporting element.

18. In an electric meter service appliance, the combination of a rear insulating supporting device comprising two separated parallel bars, two pairs of supporting elements structurally separate from the respective bars and projecting forward therefrom, an insulating base supported in part on one supporting element of each of the said pairs, and thereby held in normally fixed spaced relationship with the said bars, a pair of fuse receiving contacts on the base at the front thereof, two pairs of opposed stationary switch contacts mounted respectively on the said supporting elements, a rectilinearly movable switching member engaging at its front edge with the said base to be guided in part thereby and engaging at its near edge with the bars of the supporting device to be guided in part thereby, the said switching member comprising two spaced conducting elements movable respectively between the contacts of the said pairs to make and break electrical connection between them, an insulating member separate from the base and supported independently thereof in part on the other supporting element of one of the said pairs, and thereby held in fixed spaced relationship with the said bars, meter testing elements carried by the said separate insulating member, and an operating device for the switching member located in part in the space behind the base and the insulating member and between the supporting elements projecting forward from the respective bars of the supporting device.

In testimony whereof I have hereunto set my hand this 31st day of December, 1927.

JOSEPH SACHS.
